LIQUID DISPENSER

Gregory C. Lutz, Chicago, Ill.

Application October 30, 1952, Serial No. 317,797

5 Claims. (Cl. 222—207)

This invention relates to liquid dispensers and, more particularly, to pumps for dispensing liquid beverages such as wine, for example, from large containers.

Economically, it is most expedient for proprietors of small retail establishments to buy beverages in relatively large quantity containers and to dispense individual portions from these containers. However, it is not only exceedingly cumbersome to pour liquids from these large containers, but also a certain amount of loss of the liquid from spilling is inherent in dispensing liquids therefrom. One type of dispensing device for metering small amounts of fluid from large bodies thereof utilizes force pumps actuated by collapsible bulbs.

Conventional forms of these force pumps, however, are not satisfactory inasmuch as the contact of the liquid with the inner walls of the rubber bulb contaminates the liquid, particularly those liquids having an alcoholic content. Further, these collapsible bulb operated pumps are subject to the disadvantage that compression of the bulb often distorts the lower configuration of the bulb so that the seal between the bulb and the body of the pump is broken and the vacuum produced in the pump for raising the liquid is destroyed with a consequent decrease in the operating efficiency of the pump.

Accordingly, one object of this invention is to provide a new and improved pump for dispensing small amounts of liquid from a container holding a large quantity thereof.

Another object is to provide an improved type of force pump utilizing a collapsible bulb actuating element wherein means are provided for preventing contamination of the liquid by contact with the inner walls of the bulb.

Another object of this invention is to provide a force pump of the type actuated by a collapsible rubber bulb in which the bulb is so constructed as to prevent the destruction of the seal between the body of the pump and the collapsible bulb.

Another object is the provision of a new and improved type of pump which is easily assembled and which is provided with visible display means.

In accordance with these and many other objects, one embodiment of this invention comprises a force pump having a cylindrical body portion forming a reservoir. A collapsible bulb is mounted on the body portion by means of a flange formed integral with the bulb and the walls of the bulb immediately adjacent the flanged portion are weakened so that upon compression the bulb collapses immediately adjacent the flange portion and prevents the flange from being displaced from its position in engagement with an upper portion of the body. The reservoir or body portion is provided with an inlet, at the lower extremity of which is a one-way leaf valve, and with a spout or outlet member having a one-way leaf valve therein. When the rubber bulb is compressed, liquid within the reservoir is forced outwardly through the spout and the one-way valve associated therewith, and, upon release of the collapsible bulb, the expansion thereof closes the spout valve and opens the one-way

2

valve in the inlet so that the reservoir is refilled with a predetermined amount of the liquid to be dispensed.

A pair of baffle plates having displaced apertures there-in are interposed between the reservoir and the collapsible bulb so that, during expansion of the collapsible bulb, the liquid being drawn into the reservoir of the pump is prevented from coming into contact with the walls of the bulb. The body portion of the pump is joined with the spout or outlet member by means of a pair of spaced webbing members within which may be received a sign bearing suitable indicia representative of the liquid within the container with which the pump is associated.

The invention, both as to its organization and method of operation, together with further objects and advantages thereof, will best be understood by reference to the following specification taken in conjunction with the accompanying drawing in which:

Fig. 1 is a fragmentary side elevational view of a wine pump embodying the present invention;

Fig. 2 is a fragmentary front elevational view of the wine pump shown in Fig. 1;

Fig. 3 is a cross sectional view taken along line 3—3 in Fig. 2 and also shows a cross sectional view of the inlet valve assembly;

Fig. 4 is a sectional view taken along line 4—4 in Fig. 3, assuming that the entire pump is shown therein;

Fig. 5 is an enlarged fragmentary cross sectional view taken along line 5—5 in Fig. 1; and

Fig. 6 is an enlarged fragmentary cross sectional view taken along line 6—6 in Fig. 1.

Referring now to Figs. 1 and 2 of the drawings, there is shown a wine pump indicated generally as 20 which includes a body portion indicated generally as 22 forming a reservoir 35 (Fig. 3). Compression and expansion of a collapsible rubber bulb 24 mounted on the body portion 22 forces liquid to be dispensed through an outlet or spout 26 and draws the liquid to be dispensed upwardly into the reservoir 35 through an inlet tube 28. The spout 26 is joined to the body portion 22 by a display means or web 30 formed of transparent material.

The body portion 22, spout 26, and the display means 30 of the wine pump 20 are formed by a pair of substantially identical body elements 32 and 34, of opposite hand, which are joined together by means of a cooperating bead 36 formed around the periphery of the member 34 and a groove 38 formed around the edge of the body element 32. These two body elements are formed of a transparent or translucent material such as any of the commercial types of vinyl plastics and are cemented together so that the interlocking bead 36 and groove 38 form a liquid tight joint.

In order to fill the reservoir 35 with wine or other liquids to be dispensed, the lower portion of the body 22 formed by the two body elements 32 and 34 is provided with a locking ring 40 having a shouldered opening 41 therein to receive the upper end of the inlet tube 28. The lower end of the inlet tube 28 is provided with a one-way valve assembly indicated generally as 42 which includes a supporting member 44 and a valve plate 46 having an aperture or inlet port 48 therein. A flexible strip of vinyl plastic forms a valve element 50, and this element is secured to the valve plate 46 adjacent the inlet port 48 so that the valve element 50 covers the port 48.

In order to close the bottom opening of the reservoir 35, the locking ring 40 is provided with an annular groove 52 within which is received a depending flange 54 formed integral with the body elements 32 and 34. The locking ring 40 is cemented to the depending flange 54 so that the ring 40 not only forms a liquid-tight bond between

the ring 40 and the body 22 but also aids in maintaining the two body elements 32 and 34 in their assembled relationship to form the reservoir 35.

To secure the wine pump 20 to a large container such, for example, as a gallon jug (not shown), the ring 40 is provided with an internally threaded portion 56 which is adapted to receive the threads formed on the neck of the container, and a lower portion 58 of the ring 40 is offset to receive the shouldered portion of the neck of this container. The threaded portion 56 is provided with an aperture 59 to permit a flow of air into the container when the liquid is dispensed therefrom, thereby to prevent the creation of a vacuum in this container.

The collapsible rubber bulb 24, which is utilized to operate the wine pump 20, is secured to the upper end of the body portion 22 by means of a second locking ring 60. The locking ring 60 is provided with a depending flange 62 which engages the outer surface of a tapered annular flange 64 formed integral with the body elements 32 and 34. The locking ring 60 is cemented to the flange 64 to provide a fluid-tight seal therebetween and to aid in holding the body elements 32 and 34 in their assembled relationship. The outer surface of the locking ring 60 is also provided with an outwardly extending annular flange 66 which is received within an annular groove 68 formed in a lower flanged portion 70 of the rubber bulb 24.

When the bulb 24 is released following a compression thereof, a sub-atmospheric pressure or vacuum is produced in the bulb, and the atmospheric pressure on the body of liquid, contained within the receptacle into which the inlet tube 28 extends, forces the liquid against the flexible valve element 50 and displaces this element upwardly to a position 74 shown in dashed outline in Fig. 3 of the drawings whereupon the valve assembly 42 is opened to permit a flow of liquid up through the inlet tube 28 and the opening 41. This flow of liquid from the large container gradually fills the reservoir 35 as the rubber bulb 24 continues to expand.

The initial flow of liquid into the reservoir 35 is in the form of a jet or high velocity pulse, and in order to prevent this initial flow of liquid from contacting the inner walls of the rubber bulb 24 and thereby becoming contaminated, a tortuous path is interposed between the reservoir 35 and the interior of the collapsible bulb 24. This tortuous path is formed by providing a pair of spaced apertures 76 in the upper wall of the body portion 22 (Figs. 3 and 4) and a centrally disposed aperture 80 in the locking ring 60, which apertures place the interior of the bulb 24 in fluid communication with the reservoir 35. By virtue of the displaced positions of the apertures 76 and 80, the tortuous path formed thereby prevents a sudden gush of wine or other liquid into the reservoir 35 from entering the collapsible bulb 24.

The bulb 24 is so constructed that the volume thereof is approximately equal to the volume of the reservoir 35. Therefore, when the bulb 24 expands to produce a vacuum in the reservoir 35, the amount of liquid forced upwardly into the reservoir 35 is approximately equal to the volumetric capacity thereof. In this manner, the introduction of liquid into the bulb 24 due to an excessive amount of liquid in the reservoir 35 is positively prevented. Further, since the bulb 24 is incapable of drawing enough liquid into the reservoir 35 to overflow into the bulb 24, it is impossible for an operator to contaminate the liquid to be dispensed by completely collapsing the bulb 24.

To dispense the liquid contained in the reservoir 35, a one-way valve assembly indicated generally as 82 is interposed between the reservoir 35 and the outlet or spout 26. This valve assembly includes a valve plate 84 which is held in position by a pair of semi-circular ribs 86 formed in each of the body elements 32 and 34. The valve plate 84 is provided with a centrally disposed outlet port 88 which is normally covered by a flexible valve element 90

secured to the valve plate 84. When the bulb 24 is compressed, thereby increasing the fluid pressure on the liquid contained in the reservoir 35, the flexible valve element 50 at the lower end of the tube 28 is firmly seated against the valve plate 46 to prevent the fluid from being displaced into the container, and the flexible valve element 90 is displaced outwardly to a position indicated in dashed line at 92 whereby the fluid in the reservoir 35 flows outwardly through the outlet or spout 26. Following the displacement of the fluid contained in the reservoir 35, the release and subsequent expansion of the bulb 24 refills the reservoir 35 by attracting the flexible valve element 90 into engagement with the valve plate 84 to close the outlet valve assembly 82 and by displacing the flexible element 50 upwardly to the position indicated at 74 whereby an additional supply of liquid is drawn upwardly through the inlet tube 28.

The display means 30 for the wine pump 20 is provided by a pair of webbing members 98 and 100 formed integral with the body elements 34 and 32, respectively. When the body elements 32 and 34 are secured together, the webbing members 98 and 100 are spaced from each other to form a channel 102 within which a card (not shown) bearing suitable identifying indicia may be placed. The webbing member 98 is provided with a right angle projection 104 (Fig. 5) which extends over the channel 102 to form an entrance opening 106 through which the flexible card is inserted. The projecting portion 104 in covering the upper end of the channel 102 prevents the card from being displaced inadvertently.

In order to prevent the flanged portion 70 of the rubber bulb 24 from being displaced out of engagement with the locking ring 60, the walls of this bulb are necked down or weakened at the portions indicated by the reference numeral 110 (Figs. 1 and 3). Since the wall structure of the bulb 24 is weakened along the upper edge of the flanged portion 70, when the bulb 24 is compressed, it collapses adjacent the portions 110 and prevents the flanged portion 70 from being pivoted outwardly from engagement with the locking ring 60 thereby to prevent destruction of the fluid-tight seal between the bulb and the ring 60. Accordingly, the weakened portions 110 insure satisfactory operation of the wine pump 20 by the use of a collapsible bulb actuating means.

The wine pump 20 is well adapted for use in dispensing comestible beverages inasmuch as it may easily be disassembled for cleaning by removing the rubber bulb 24 from engagement with the locking ring 60. Once this bulb is removed, the reservoir and inlet tube of the reservoir 35 and inlet tube 28 may be cleaned by introducing suitable cleaning fluids through the apertures 76 and 80. By placing these cleaning fluids under pressure, the valve element 90 will be displaced outwardly so that the cleaning fluids flow through the outlet or spout 26 to remove any material which may have accumulated therein.

Also, since the wine pump 20 is formed of translucent or transparent material, it is well adapted for dispensing a predetermined amount of liquid inasmuch as the level of the liquid in the reservoir 35 is easily ascertained by visual inspection, and all of the working elements of the wine pump 20 may be visually checked to determine whether or not they are functioning properly.

While a particular embodiment of the invention has been shown, it will be understood, of course, that the invention is not limited thereto since many modifications may be made, and it is therefore contemplated by the appended claims to cover any such modifications as fall within the true spirit and scope of the invention.

What is claimed and desired to be secured by Letters Patent of the United States is:

1. A liquid dispenser comprising a reservoir having a plurality of spaced apertures therein, means mounted on the reservoir adjacent the apertures and having a single opening displaced therefrom, a collapsible bulb mounted

on said means and in fluid communication with the reservoir through said apertures and opening, and liquid inlet means opening into the reservoir opposite the apertures.

2. A liquid dispenser comprising a body forming a reservoir, a collapsible diaphragm mounted on the body and in fluid communication with the reservoir, inlet means for introducing liquid into the reservoir, outlet means in communication with the reservoir for discharging liquid therefrom, and spaced webbing means positioned between the outlet means and the wall of the body to provide a channel for receiving an indicia bearing medium.

3. A liquid dispenser for use with a container comprising a body forming a reservoir, a collapsible diaphragm carried by the body and in fluid communication with the reservoir, inlet means for introducing liquid into the reservoir, outlet means for discharging liquid from the reservoir, visible display means including two spaced webbing members integral with the outlet means and the body and extending therebetween, and means carried by the body and positioned around the inlet means for detachably mounting the dispenser on the container.

4. A dispenser comprising means defining a fluid reservoir, displaceable means for moving fluid into said res-

ervoir, and means placing said reservoir and said displaceable means in fluid communication, said communication means including a pair of spaced plates having nonregistering openings therein.

5. A dispenser comprising means defining a fluid reservoir, displaceable means for moving fluid into said reservoir, and means defining a tortuous passageway placing said reservoir in fluid communication with displaceable means, said passageway means including a pair of spaced plates forming a cavity and having at least one opening in each of said plates out of registration with the opening in the other of said plates to place said cavity in communication with said reservoir and said displaceable means.
